UNITED STATES PATENT OFFICE.

JOSEPH WHITE, OF PITTSBURG, KANSAS.

RAILROAD-SPIKE.

1,206,629.

Specification of Letters Patent. Patented Nov. 28, 1916.

Application filed March 29, 1916. Serial No. 87,533.

To all whom it may concern:

Be it known that I, JOSEPH WHITE, a citizen of the United States, residing at Pittsburg, in the county of Crawford and State 5 of Kansas, have invented new and useful Improvements in Railroad-Spikes, of which the following is a specification.

This invention relates to improvements in spikes of that type adapted for securing a rail upon a rail tie, and so designed to facilitate the engagement of the spike with both the base and head portions of such rail. To this end, use is made of a spike having an apertured head adapted for engagement 15 with the base portion of a rail for securing the latter upon a rail tie, and a movable locking member provided with a depending pin for engagement in the aperture of the head portion of said spike for rotatably mounting the locking member thereon, and means formed integral with the movable locking member for preventing the breakage or displacement of the pin from the head of the spike.

With the above and other objects in view, the invention consists in the novel features, details of construction, and combination of parts which will hereinafter be more fully set forth, illustrated in the accompanying 30 drawing, and pointed out in the appended claim.

Figure 1 is a vertical section of a rail and tie, illustrating my invention used in connection therewith; Fig. 2 is a top plan view, 35 with the head portion of the rail removed therefrom; Fig. 3 is a perspective view of the spike; and Fig. 4 is a perspective view of the movable locking member.

Referring more particularly to the accompanying drawing, in which like characters of reference refer to corresponding parts in the several views, 1 designates a rail, and 2 a rail tie.

My improved form of spike consists of a 45 spike proper 3, and a movable locking member 4.

The spike 3 comprises a shank 5 formed with a pointed lower extremity 6, whereby the shank of the spike may be driven in the 50 tie 2, as shown. A head 7 is formed on the upper end with a prong 8, adapted to be driven in the tie for retaining the head in engagement with the base 9 of the rail 1, as clearly shown in Fig. 1 of the drawing.

55 The portion of the head contacting with the base of the rail is formed with a cylindrical

opening 10, which extends vertically through the head.

The movable locking member 4 comprises an elongated shank portion 11. Formed on the lower end 12 thereof, and depending therefrom is a cylindrical pin 13. It will be apparent from the drawing that when this movable locking member is in active position, the pin 13 thereof is inserted in the opening 10 of the head 7 for movably and rotatably mounting the locking member 4 upon the head 7 of the spike proper. This locking member is swiveled with such head by offsetting the lower end thereof, indicated by the character 14, and by so doing, will prevent the displacement of the locking member from the head upon the bending of the locking member in engagement with the head of the rail, as further disclosed in Fig. 1 of the drawing. The shank 11 of the movably locking member is provided with a head 15, including a laterally projecting lip 16 adapted for engagement beneath the under surface 17 of the head of the rail. As before stated, when it is desired to lock the movable locking member with the head 18 of the rail, the said locking member is rotated to bring the lip 16 in confronting relation with the web of the rail, after which the same is bent to assume a vertical inclined position, and to bring the lip 16 to bear against the under surface of the rail head. The bending action of this movable locking member, places considerable strain upon the pin 13, which is liable to break the pin, or withdraw such from the opening 10 of the head 8 of the spike proper, and to prevent the movable member being bent any more than is really necessary, I have provided the head 15 of the movable member with a vertically extending projection 19, which abuts with the longitudinal side faces of the rail head, and prevents any further bending action of the movable locking member than is necessary to accomplish the engagement of the lip 16 with the head portion of the rail. This projection is formed flush with the rear face 20 of the locking member and at right angles to the lip, and extends beyond the plane thereof, thereby constructing the head 15 of the rail of substantially L-shaped configuration.

From the foregoing description, taken in connection with the accompanying drawing, the advantages of construction and of the method of operation will be readily apparent

to those skilled in the art to which the invention relates, and while I have described the principles of operation of the invention, together with the device which I now consider 5 to be the best embodiment thereof, I desire to have it understood that the device shown is merely illustrative, and that such changes may be made when desired as are within the scope of the claim appended hereto.

10 I claim:

A spike comprising an apertured head, provided with a shank for engagement with the rail tie, a locking member therefor, said locking member embodying a shank, a head 15 formed on the upper end of said shank and including a horizontally extending lip, a pin depending from the lower end of the shank, and adapted to be inserted in the opening of the head of the spike and swiveled therein,

said locking member adapted to be bent to 20 assume an inclined position for positioning the horizontal lip thereof in binding engagement with the under portion of the head of a rail, and a vertically extending projection formed integral with the head of the locking member and extending at right angles to the horizontally projecting lip thereof, said projection adapted to engage with the longitudinal side edges of the rail head for preventing the displacement of the pin from the 30 head of the spike, substantially as and for the purpose specified.

In testimony whereof I affix my signature in presence of two witnesses.

JOSEPH WHITE.
